UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER OR LOOSE-SHEET HOLDER.

1,222,705.

Specification of Letters Patent. Patented Apr. 17, 1917.

Continuation in part of application Serial No. 15,590, filed March 19, 1915. This application filed January 20, 1916. Serial No. 73,209.

To all whom it may concern:

Be it known that I, GEORGE P. WIGGINTON, a citizen of the United States, residing at Kalamazoo, county of Kalamazoo, State of Michigan, have invented certain new and useful Improvements in Temporary Binders or Loose-Sheet Holders, of which the following is a specification.

This invention relates to improvements in temporary binders or loose sheet holders.

In the use of temporary binders for holding record sheets or leaves on which it is desired to keep records in typewriting a binder which permits the ready removal and insertion of the sheets without undue wear on the sheets is of great advantage. I have shown such a binder in my Patent No. 1,174,458, issued March 7, 1916, and this application is a division thereof to the extent that the embodiment shown in Figures I, II and III was originally disclosed in that application and that certain claims of this application have been transferred from that application to this. I, however, show still another embodiment of my invention herein.

The main objects of this invention are:

First, to provide an improved temporary binder or loose sheet holder of the post type which permits the rapid insertion or removal of sheets or leaves and at the same time one in which the sheets are securely held when the binder is adjusted to retain the sheets, the sheets being freely removable when the binder is adjusted to release the sheets.

Second, to provide an improved temporary binder of the post type having these advantages, which is easy to manipulate and is simple and economical in structure.

40 Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated 50 in the accompanying drawing, forming a part of this specification, in which:

Fig. I is a detail section on a line corresponding to line 1—1 of Fig. II, of a struc-

ture embodying the features of my invention.

Fig. II is a detail section on a line corresponding to line 2—2 of Fig. I, the removable post being shown in full lines.

Fig. III is a detail view of the adjusting means of the embodiment shown in Figs. I and II.

Fig. IV is a detail longitudinal view, showing the binder illustrated in Fig. I arranged in a rack or support.

Fig. V is a plan view illustrating the removable posts of different lengths.

Fig. VI is a detail perspective view of another embodiment of my invention, the same being a sectional post binder.

Fig. VII is a detail longitudinal section of the structure appearing in Fig. VI in the plane of one of the sectional posts, the sectional post being shown partially in full lines.

Fig. VIII is a detail longitudinal section in the plane of one of the removable posts, the removable post being shown in full lines.

Fig. IX is a detail section on a line corresponding to line 9—9 of Figs. VII and VIII.

In the drawing similar reference characters refer to similar parts throughout the several views, and the sectional views are taken looking in the direction of the little arrows at the ends of the section lines.

Referring to the drawing, 1—1 represents the covers and 2—2 the clamping or binder members to which the covers are hinged. The clamping members 2 are provided with flanges 3 which telescope with the back 4. The back 4 constitutes a support for the adjusting screw 5 which is mounted in a center block 6 and oppositely threaded to engage the adjusting members 7. These adjusting members carry arms 8 which engage the inclined slides 9 on the clamping members so that when the adjusting members are moved outwardly by the screw the clamping members are separated. The clamping members are connected with the 100 adjusting members by chains 10 which pass over pulleys 11 so that when the adjusting members are moved inwardly by the screw the clamping members are drawn together and clamped upon the sheets or leaves. 105 The parts thus described are those of a

binder commonly known as a "metal back" current binder, and as the adjusting features form no part of my present invention and are well known in the art I do not describe the same with further detail herein.

5 The clamping members carry permanent or relatively fixed posts formed of telescoping sections 12 and 13. They are also provided with opposed pairs of sockets 14 adapted to receive the ends of the removable posts 15.

10 The sheets 16 are provided with notches 17 open at the binding edges of the sheets and spaced to engage the relatively fixed posts 15 and holes 18 adjacent the binding edges and adapted to receive the removable posts when the sheets are arranged with their notches in engagement with the fixed posts.

15 The notches and holes are so spaced that the notches may be engaged with the posts with the sheets in an alined body or they may be arranged with part of the sheets in an offset relation with at least one notch of each sheet engaging one of the relatively 20 fixed posts. It will be obvious that the sheets may be offset on either side. The holes are so spaced relative to the notches that the removable posts can be inserted in the holes when the sheets are arranged in an 25 alined body or when arranged with part of them offset in each direction, and when the removable posts are engaged and the clamping members 2 adjusted upon the same the sheets cannot be removed. When however, 30 the clamping members are retracted and the removable posts removed the sheets are entirely free. The permanent posts however serve as a means for properly alining them to receive the removable posts and, as stated, 35 they are properly alined either in a body or 40 in an offset relation.

45 In Fig. IV I show my improved binder arranged in a rack consisting of a base 20 and side members 21, the side members being adapted to support the covers when the binder is disposed between them upon the base. This rack facilitates the use of the binder supporting the sheets so that they can be conveniently removed to receive 50 record and readily be inserted.

55 The removable posts are made in several lengths, a post being selected according to the thickness of the sheet body. I illustrate these posts of different lengths in Fig. V.

60 In the embodiment shown in Figs. VI, VII, VIII and IX I show my improvements adapted to a sectional post binder consisting of binder members 22 and 23 having covers 24 hinged thereto. The binder member 22 is provided with threaded sockets 25 for the sectional posts 26 while the binder member 23 may be slipped over the post and pushed down upon the sheet body.

65 The binder member 23 is provided with a

clutch mechanism 28 coacting with the posts to retain the binder member 23 in its adjusted positions thereon. The structural details of this mechanism are not further illustrated as suitable mechanisms are well known. The binder members 23 and 24 are provided with sockets 29 and 30, respectively, for the removable posts 15 which are retained by adjusting the binder or clamping members thereto, substantially as in the 70 75 embodiments shown in Figs. I-III.

The sheets are notched and perforated substantially as described in connection with the structure shown in Figs. I-III, and the sheets may be manipulated in the same manner. The binder members are, however, completely separable and the structure is therefore adapted for use in a rack or supporting device such as is illustrated in Fig. VI, the rack being similar to that shown in the application of George Farron, filed 80 March 11, 1915, Ser. No. 13,826. The binders thus effectively support and retain the sheets and are capable of very convenient and rapid manipulation with a minimum of 85 wear and injury to the sheets, and at the same time when the binder is adjusted to the sheets they are very securely and effectively retained and bound.

I have not attempted to illustrate or describe all the modifications and adaptations which I contemplate or which might be desirable for adapting my improvements to particular types of binders, as I believe the disclosure made will enable those skilled in the art to which my invention relates to embody or adapt the same as may be desired.

Having thus described my invention, what I claim as new and desire to secure by Letters Patent, is:

1. In a temporary binder, the combination of binder members provided with relatively fixed posts and opposed post sockets, means for adjusting said binder members, removable posts adapted to be engaged with said sockets and being freely removable therefrom when said binding members are separated, and sheets having notches open at their binding edges and holes adjacent their binding edges, said removable posts being adapted to be inserted through said holes in said sheets, said notches being adapted to be engaged with said relatively fixed posts.

2. In a temporary binder, the combination of adjustably associated binder members, an extensible relatively fixed post operatively associated with said binder members, removable posts of different lengths adapted to be removably associated with said binder members, and sheets having U-shaped notches open at their binding edges adapted to be engaged with said permanent post, and holes adjacent their binding edges adapted to receive a removable post when 120 125 130

the notches are engaged with said permanent post.

3. In a temporary binder, the combination of a pair of binder members provided with relatively fixed extensible posts and having opposed post sockets in their inner faces, means for adjusting said binder members, and removable posts of different lengths adapted to be removably engaged in 10 said sockets and retained therein by the adjustment of the binder members thereto and being freely removable therefrom when the binder members are separated.

4. In a temporary binder, the combination 15 of binder members provided with open post sockets, permanent posts extending between said binder members, and posts removably engaged in said sockets, said removable posts being retained in said sockets by the 20 adjustment of the binder members thereto and being freely removable from said sockets when the binder members are separated.

5. The combination in a loose leaf binder 25 of binder members and binding posts, at least one of said posts being removably associated with said binder members, and sheets provided with a plurality of open notches in their binding edges spaced so 30 that the sheets may be arranged in an alined body or part in different lateral positions with alined notches engaging one of the posts, said sheets also having a plurality of holes adjacent their binding edges 35 uniformly spaced relative to each other and relative to said notches so that there are registering holes adapted to receive a removable post when the sheets are arranged in an alined body or in different lateral positions with their notches registering.

6. In a temporary binder, the combination 45 of binder members having a relatively fixed post and a removable post associated therewith, and sheets having open unobstructed notches at their binding edges adapted to be engaged with said fixed post and holes adjacent their binding edges adapted to receive said removable post when the notches are engaged with said 50 fixed post, the removable post retaining means of said binder members being within the planes of their sheet binding faces so that when the removable post is removed the sheets are all released and the sheets collectively as a unit or individual sheets may be 55 freely disengaged from or engaged with said fixed post.

7. The combination of sheets having holes 60 adjacent their binding edges and notches open at their binding edges, and binder members provided with a relatively fixed post and a removable post, said notches of said sheets being adapted to be engaged with said relatively fixed post with the 65 sheets in alinement or in different lateral

relations, said holes being adapted to receive said removable post when the notches are engaged with said fixed post.

8. The combination of sheets having holes adjacent their binding edges and notches open at their binding edges, and binder members provided with posts, the said notches of said sheets being adapted to be engaged with one post with the sheets in an alined body or in different lateral relations, said holes being adapted to receive another post when the sheets are in an alined body or in different lateral relations.

9. In a temporary binder, the combination 75 of binder members, binding posts and sheets having notches open at their binding edges and holes adjacent their binding edges disposed so that the sheets may be supported in an alined body with a post engaging said holes or selected sheets may be supported 80 in an offset relation to the body of the sheets 85 with their notches engaging a post.

10. In a temporary binder, the combination 90 of binder members provided with relatively fixed and removable posts, and sheets having notches open at their binding edges adapted to be engaged with said fixed posts and holes adjacent their binding edges adapted to receive said removable posts when said notches are engaged with said 95 fixed posts, said notches and holes being uniformly spaced.

11. In a temporary binder, the combination 100 of binder members provided with a relatively fixed post and a removable post, and sheets having unobstructed notches at their binding edges adapted to be engaged with said fixed post and holes adjacent their binding edges adapted to receive said removable post when the notches are engaged 105 with said fixed post, the removable post retaining means of said binder members being within the planes of their sheet binding faces so that all the sheets are released by the withdrawal of said removable post and 110 the sheet body as a unit or individual sheets may be freely engaged and disengaged with said fixed post by longitudinal movement of the sheets.

12. In a temporary binder, the combination 115 of a pair of binder members provided with a relatively fixed post and having opposed post sockets within the planes of their inner faces, means for adjusting said binder members, and a removable post engaged in 120 said sockets, said removable post being retained in said sockets by the adjustment of the binder members thereto and being freely removable from the sockets when the binder members are separated.

13. In a temporary binder, the combination 125 of a pair of binder members provided with a relatively fixed post and having opposed post sockets within the planes of their inner faces, a removable post engaged in 130

said sockets, and sheets having holes adjacent their binding edges adapted to receive said removable posts and U-shaped notches open at their binding edges adapted to engage 5 said fixed post so that the sheets may be engaged and disengaged therewith individually or a plurality of sheets collectively as a unit by a longitudinal movement.

14. The combination of sheets having 10 holes adjacent their binding edges and U-shaped notches open at their binding edges and binder members provided with a relatively fixed post and a removable post, said notches of said sheets being adapted to be 15 engaged with said relatively fixed post, said holes being adapted to receive said removable post when the notches are engaged with said fixed post, whereby the entire leaf body is free when said removable post is removed 20 and may be engaged and disengaged collectively as a unit with said fixed post.

15. In a temporary binder, the combination of a pair of adjustably associated binder members provided with opposed post sockets, an extensible relatively fixed post operatively associated with said binder members, and removable posts of different lengths adapted to be removably engaged in said 25 sockets and retained therein by the adjustment of the binder members thereto.

16. In a temporary binder, the combina-

tion of adjustably associated binder members, an extensible relatively fixed post operatively associated with said binder members, and removable posts of different 35 lengths adapted to be removably associated with said binder members.

17. In a temporary binder, the combination of a pair of adjustably associated binder members provided with opposed post sockets, an extensible relatively fixed binding member operatively associated with said binder members, and removable posts of different 40 lengths adapted to be removably engaged in said sockets and retained therein 45 by the adjustment of the binder members thereto.

18. In a temporary binder, the combination of adjustably associated binder members, an extensible relatively fixed binding member operatively associated with said binder members, and removable posts of different 50 lengths adapted to be removably associated with said binder members.

In witness whereof, I have hereunto set 55 my hand and seal in the presence of two witnesses.

GEORGE P. WIGGINTON. [L.S.]
